DESIGN FOR A CHARM OR SIMILAR ARTICLE OF JEWELRY

Pierre Cherdakoff, University City, Mo.

Application May 18, 1942, Serial No. 106,940

Term of patent 3½ years

To all whom it may concern:

Be it known that I, Pierre Cherdakoff, a citizen of the Republic of France and a resident of the city of University City, county of St. Louis, and State of Missouri, have invented a new, original, and ornamental Design for a Charm or Similar Article of Jewelry, of which the following is a specification, reference being had to the accompanying drawing, forming a part thereof.

In the drawing:

Fig. 1 is a top plan view of a charm or similar article of jewelry, showing my new design;

Fig. 2 is a front elevational view thereof, and Fig. 3 is a side elevational view thereof.

I claim:

The ornamental design for a charm or similar article of jewelry, substantially as shown.

PIERRE CHERDAKOFF.
